METHOD AND APPARATUS FOR RADIOSIGNALING.

1,273,431.

Specification of Letters Patent. Patented July 23, 1918.

Application filed January 6, 1916. Serial No. 70,571.

To all whom it may concern:

Be it known that I, ROY A. WEAGANT, a citizen of the United States, residing in the town of Roselle, county of Union, State of New Jersey, have made certain new and useful Improvements in Methods of and Apparatus for Radiosignaling, of which the following is a specification.

This invention relates to improvements in the art of and apparatus for radio signaling and employs a receiving antenna constructed to exclude interfering electromagnetic waves of a frequency considerably higher than the frequency of the incoming waves to which the receiving apparatus is adapted and adjusted to respond as in the process of receiving signals due to the transmission from a distant station, and to do this in a more effective manner than has heretofore been found possible. The object of the improvement is to avoid interfering electromagnetic waves of different frequency than, for the time being, are used for signaling.

It is commonly noted that while an aerial or antenna system, by means of the ordinary tuning methods, can be so adjusted as to respond to a maximum extent to electromagnetic waves having a definite period yet it is also commonly observed that such an aerial system will oscillate at its own period when excited by electromagnetic waves having a widely different period; this is exceptionally true when such different magnetic waves are quite strong or emanate from a nearby, powerful transmitter, or are the result of static disturbances. The purpose of this invention is to make the antenna system less responsive to disturbances of this sort or character.

The usual arrangement of elevated wire is or may be employed; but included, preferably at regular intervals, there are fixed inductances which may be of substantially equal value and in the form of closely wound coils. This antenna is associated with a receiving circuit having well known, adjustable means for tuning and it results from the construction and arrangement described that, when receiving electromagnetic waves of predetermined frequency waves of higher frequency or shorter wave lengths are effectively excluded.

While experimenting with the large receiving aerial constructed by the Marconi Company at New Brunswick, New Jersey, which aerial has a natural period of approximately 7,000 meters, I found great difficulty in eliminating interference due to stations having a wave length quite short in comparison; say, from 600 to 3,000 meters, and that the usual methods of tuning would not effectively eliminate these interfering waves. I conceived that the reason for this was the fact that the inductance and capacity of the antenna were distributed in a uniform manner and that, therefore, the aerial itself was capable of vibrating at periods other than its fundamental. It appeared to me, also, that the remedy for this condition was in an aerial constructed with a number of inductance coils located at separated points throughout the length of the antenna and I therefore constructed such an aerial at the laboratory of the Marconi Company in Union county, New Jersey, and I found that its effect in this respect was very great. When listening to signals transmitted, for instance, from Nauen, Germany, with the ordinary type of antenna the operation of testing transmitters in course of manufacture in the factory building immediately adjacent to this antenna, but not connected to it, made such reception entirely impossible and that furthermore, a number of other stations, such as New York navy yard, Sea Gate, New York, and others, caused a sufficient disturbance to greatly interfere with reception of signals from Nauen, the wave length of which station is understood to be, approximately, 12,000 meters, while that of the interfering stations named ranges from 600 to 2,000 meters. When, however, my novel type of aerial is employed, other conditions being identical, I have found that it is possible to receive these signals from Nauen without interference from the other stations named. I also find that this antenna is most effective when receiving continuous oscillations and its receiving efficiency, as compared to an ordinary antenna, is greater when receiving continuous oscillations than it is when receiving damped oscillations.

The accompanying drawings illustrate the invention. Figure 1 shows my improved re-

ceiving antenna; Fig. 2 is a modification; Fig. 3 shows a coöperating transmitting circuit at a distant point or station.

In each figure of the drawing there is an antenna *a*. In Fig. 1 there are a series of inductance coils, which may be closely wound coils *i*, of insulated wire, preferably of equal dimensions and substantially equidistant from each other. There is also the usual inductorium having one coil 10 in the antenna *a* coöperating with coil 11, in the closed oscillating circuit; coil 11 is bridged by an adjustable condenser 12 and there is a detector 14, of any suitable kind, telephone receiver 15 or other indicating instrument and a bridging condenser 16. In Fig. 2 the antenna *a*, has a horizontal section 20, of considerable extent, suitably supported on towers or other supports 21. Inductance coils *i* are connected at intervals in the antenna *a*, the same as in Fig. 1. In Fig. 3 there is shown a motor generator arrangement 30; the generator is a high frequency alternating current generator 31 in a circuit 32 which includes a Morse transmitting key 33; there is the primary coil of an inductorium, 34, having a secondary coil 35 with magnetic wire core 36; coil 35 is in the closed oscillating circuit with a condenser 37, a quenched gap 38, and the primary coil of a transformer 39 having an adjustable secondary coil 40 in the antenna *a*.

During regular normal operation of the transmitter oscillations of predetermined frequency are apparent in the antenna *a* of the receiving stations, Figs. 1 and 2. While receiving the transmitted signals, at such receiving station, any interfering signals or impulses from whatever source, or any source, either natural or artificial, of greater or higher frequency than, at the time, is being used for the described signaling are non-interfering and are not apparent in the receiving apparatus. This is due to the presence in the receiving apparatus of the described series of inductances, or concentrated inductance, in the receiving antenna imparting a fundamental characteristic to the antenna which appears to block out oscillations of higher frequency.

The operation of my improved apparatus may be in part explained as follows, although it is not to be understood as being a definite explanation of its entire action: An ordinary antenna has inductance, resistance and capacity constants more or less uniformly distributed throughout its length. It results from this that the antenna may be caused to vibrate, as described above, at its own periodicity, either by repeated applications of minute impulses at the frequency of the antenna, as by received oscillations from the sending station, or by a species of electrical shock, such as might be caused by one or more uni-directional im-

pulses or oscillatory impulses of relatively great strength, but of a periodicity different from that of the antenna. Such impulses, as I have stated above, may proceed from a neighboring transmitting station, or from static disturbances.

In my improved device, by distributing the constants of the antenna throughout its length, in a uniform manner, as by connecting concentrated inductances at intervals (not necessarily regular) along the antenna in any desirable manner, the antenna is so constituted that it will not respond to shock, but will nevertheless be entirely responsive to repeated applications of energy. A species of electrical inertia, so to speak, has thus been imparted to the system, which resists the wide oscillations produced by shock, but does not prevent the setting up of oscillations by the repeated application of energy at the periodicity of the antenna. This is probably due to the fact that the subdivision of the antenna into several parts, by the inclusion of the concentrated inductances, permits the electromotive force of the shock oscillation to be propagated a limited distance only along the antenna before meeting with a reflection point, or point of abrupt change of constants, such reflecting points producing increased effects at higher frequencies.

While I have described my method and apparatus in connection with a receiving station for radio telegraphy, that being a connection in which it displays marked usefulness, it will be obvious to those skilled in the art that it may be used to eliminate undesired electrical oscillations, whether proceeding from static interference, or other sources, at a sending station, as, for instance, when an arc generator of high frequency oscillations is employed, and that it may be used either for radio telegraphy or radio telephony.

While I have conclusively proven the beneficial and novel results to be obtained with my construction in connection with interference due to disturbances of higher frequency or shorter wave length than that to which my new aerial is tuned, I have not had equal opportunity to test it against interference or from disturbances of greater wave length. I have, therefore, largely confined my description to the exclusion of such higher frequencies. While I cannot state it with equal certainty, I believe it to be the fact, from such tests as I have been able to make, that it is of great benefit in preventing interference from longer waves than those to which the aerial is turned, and I do not desire to limit my claims in this respect, other than by the construction set forth in them.

I have actually used fixed inductances of equal value and at regular intervals, and I

have found this structure effective, but I do not limit myself in this regard, except as specified in my claims:

What I claim is:

- 5 1. In apparatus of the kind described, an open antenna circuit system having means for producing a plurality of reflection points distributed substantially throughout its length.
- 10 2. The method of radio signaling which consists in setting up oscillations in an open antenna by repeated applications of impulses at a desired frequency, and setting up at points throughout the antenna reactions opposed to oscillations of undesired frequencies.
- 15 3. In apparatus of the kind described, an antenna consisting substantially throughout its length of a plurality of sections having distributed capacity and inductance only and connected to each other by inductance coils through which the current

passing from one to the other is forced to flow.

4. In apparatus of the kind described, a receiving open antenna having adjustable inductance therein and having at points outside said adjustable inductance and distributed throughout the length of said antenna, a plurality of concentrated inductances, in combination with means, at a distant station, for generating and transmitting oscillations of coöperating characteristics.

5. The method of radio signaling which consists in setting up oscillations in an open antenna by repeated applications of impulses at a desired frequency, and setting up at points distributed substantially throughout the length of the antenna reactions opposed to oscillations of undesired frequencies.

ROY ALEXANDER WEAGANT.
